 Filed Oct. 16, 1962, Ser. No. 230,918
 4 Claims. (Cl. 29—243,53)

This invention relates to a crimping tool, for bending the edges of sheet metal, and in particular, to an attachment for air hammers or the like, for providing the closing and sealing fold in a corner interlock in metal ducts, commonly known as the "Pittsburgh lock." Present-day requirements in this field of operations are, of course, enormous in extent, and on-site closing operations for this type of metal work have long since outmoded the slow and laborious method, using an ordinary hammer. However, although special crimping tools have been proposed from time to time, these have not found acceptance to any noteworthy degree, for various reasons, such as unduly complex structure, high cost, and lack of versatility and adaptability.

It is therefore a general object of the invention to provide a crimping tool which is simple in structure, and readily portable. Another object is to provide a tool which reduces to a minimum, the requirements for special skill in operation. More particularly, it is an object to provide a tool for progressive crimping of a corner fold, having inherent guiding and spacing features.

In still greater particular, it is an object to provide a reciprocating, crimping tool which, in addition to the advantageous appertaining to the foregoing objects, is capable of simple adjustment for multi-stage crimping operations, for dealing with less tractable materials. A related object is to provide a crimper which is adjustable in orientation.

Yet another object is to provide a tool as aforesaid, which, in addition is capable of employment with a power-impact tool, or manually delivered blows, as with a hammer, the guidance, precision and speed being supplied by the tool in either case.

Another object is to provide a reciprocating, crimping tool, having a mount which also functions as a back-up dolly.

It is also among the objects to provide a tool which is easy of manufacture, and low in cost.

These and other ends, which will be apparent, are attained by the present invention, a preferred form of which is described in the following specification, as illustrated in the drawings, in which:

FIGURE 1 is a perspective view of a tool, according to the invention, applied to the interlocking corner of a sheet-metal duct, in the course of the first stage of a two-stage crimping operation.

FIGURE 2 is a perspective view of the corner of a duct having the interlocking fold, showing the completion of the first stage of crimping indicated as in progress in FIGURE 1.

FIGURE 3 is a perspective view of the tool in the course of applying the second, and final, stage of crimping.

FIGURE 4 is a view similar to FIGURE 2, showing the completion of the second, and final, stage of crimping, shown in progress in FIGURE 3.

FIGURE 5 is a front elevational view of the tool, as seen from the right of FIGURE 1.

FIGURE 6 is a vertical section through the middle of the tool, taken on the plane of the line 6—6 of FIGURE 5.

FIGURE 7 is a view similar to FIGURE 6, with the tool parts adjusted to the relative positions shown in FIGURE 3, and

2

FIGURE 8 is a sectional view taken on the line 8—8 of FIGURE 7.

Referring to the drawings by characters of reference, there is shown, in FIGURE 1, a fragment of rectangular, sheet-metal conduit, with a side wall 10, having an S fold 12, with a flattened, inner loop 14, and an outer loop 16, with its outer side extending above the bight at the top of loop 14, and spaced therefrom to define a channel having a width about equal to the thickness of the metal. The top wall 18 is bent at right angles near its free edge, producing a depending skirt 20, which nests in the said groove of the S fold, in the closed position of the conduit, and the assembly is sealed by bending, or crimping, the upper portion of outer loop 16, to the position shown in FIGURE 4. This corner interlock is known as the "Pittsburgh lock," and it is a prime purpose of the invention to facilitate the folding, or crimping operation involved.

The crimping tool, in the preferred embodiment illustrated, comprises a main body, or block 22, which serves the plural functions of providing a mount for the impacting hammer, or ram, of guiding the progress of the tool in an operative path, along the work, and of serving as a back-up dolly. To these ends, the block 22 is relatively massive, and has at least one flat face 24, on its inner side, for planar engagement with the outer surface of conduit side wall 10. Conveniently, the block 22 is of uniform thickness, so that its outer face is also planar, and, as shown, the height and width are roughly comparable, with the height somewhat greater. For holding it steady against the work, the block carries a handle 26, threadedly secured in the block, and extending from its outer face. The block also has a U-form notch 28, medially of its upper edge, providing clearance for the swingable, reciprocable, impact unit, presently to be described.

Block 22 has a further, spacing and guide means, positioning it relatively to top wall 18, comprising a 90° angle member, having end tabs 30, secured by welding to the top of the block, on opposite sides of notch 28, and a depending skirt 32, adapted to contact top wall 18 of the conduit, and thus space the block 22 with respect to the plane of top wall 18. In particular, the height of skirt 32 is such that the tabs 30 clear the top edge of the S section 16, prior to folding. Also the skirt 32 is spaced from block 22 at a distance sufficient to accommodate the portion to be folded over. Preferably this spacing is substantially equal to the width of the folded portion, so that the skirt forms a positive guide means during crimping, by engaging the edge of the folded portion, and thus holding the block against the work. Between the tabs 30, skirt 32 has a U-shaped notch 34, medially of its length, which assists in observation of progress of the work, and also provides clearance for the reciprocating hammer unit, as required.

The hammer unit comprises a cylindrical rod 36, slidably mounted in a sleeve, or cylinder 38, which is swingably mounted on block 22 by means of a bail-like arrangement comprising a pair of curvate struts 40, with upper ends welded, or otherwise secured, to opposite sides of sleeve 38, near the top thereof, and having inturned, bent, lower ends 42, of circular cross section, received in suitable bores in the respective, side edges of block 22, and constituting trunnions, for the swinging movement of the hammer unit, as a whole.

Rod 36, which forms the reciprocating hammer element providing the impacts for the work, has a lower, mushroom type head 44, which is the contact element in impacting the work, and which also limits upward movement of rod 36 in sleeve 38. The rod 36 is normally held in its extreme upper position, with head 44 in contact with the bottom edge of sleeve 38, by means of a compression, coil spring 46, surrounding rod 36, with its lower end abutting the top edge of sleeve 38, and its upper end contacting a washer 48, the latter held against upward movement by a

split, spring ring retainer 50, carried in an annular groove in rod 36, in a reduced end 52 of the rod, at the shoulder formed thereby. Thus, the rod, or hammering ram, 36 may be moved downward, against the bias of spring 46, in response to an impacting force, which may be applied by an air or electrical impact hammer having an adaptor with a cavity adapted to receive the reduced end 52, such as the collet 54 shown in dash lines in FIGURES 1 and 3. Obviously, the ram will be of suitable hardness, at least at the ends, to withstand the rough usage.

As seen in FIGURES 6 and 7, the struts 40 are arranged at a small, oblique angle to the axis of the hammer unit, for proper mechanical advantage in the crimping operations, as will be seen.

For the first stage of the two-stage crimping operation, the back-up dolly and mounting block 22 is applied to the side wall 18, with skirt 32 dwelling on top wall 18, and the hammer unit is swung on its trunnions to about the position shown in FIGURE 6. The exact angular position is not critical, and the operator will soon determine the most favorable angle applicable to his own technique. Also, it is possible to vary the angle of the hammer during the progress of the initial bending stage. However, it is most expedient to select an angle and maintain it throughout the first stage, so that progress along the line of crimping is uninterrupted. Experience has shown that an angle which produces a fold of about 45° in the first stage is to be preferred. However, the factors involved are variable, and a different angle may be called for in some cases.

In FIGURE 6, the head 44 of the hammer is shown, in broken lines, in two positions of folding, at a given station along the work, with the first position showing contact with the work, and before any folding occurs, and the second position showing the element 16, in broken lines, forced into the 45° folded condition. It should be understood that this operation, although involving a plurality of impacts, is almost instantaneous, so that the tool is slowly, but continuously moved along the line of work.

The 45° folded condition of element 16 is shown in full lines, in FIGURE 7, and here, the hammer unit is shown as swung into a substantially vertical position, for a second run along the work to complete the seal by further folding element 16 into 90° disposition, and contact with the outer surface of top wall 18. Here, it will be noted that the angular disposition of struts 40 with respect to the axis of the hammer unit, compensates for the offset location of block 22, and enables positioning of the hammer directly over the strip being folded. As in the case of the first-stage position of the hammer, its exact orientation is not critical, and the opening 34 in the skirt 32 will provide some clearance for a degree of obliquity in the hammer system, if such be deemed necessary or desirable.

As stated above, the block 22 serves, among other things, as a back-up dolly, and in the closed system of block and reciprocating hammer, the ultimate thrust of the hammer is absorbed by the block. As shown, the head 44 of the hammer overlaps the block somewhat in all positions of the hammer, and this overlap may be varied, for any given tool, over a reasonable range.

In operation, the handle 26 is held in one hand, to completely position the tool, and the air or electrical impact hammer is held in the other hand of the operator. Obviously, it is also possible to operate with the use of an ordinary hammer to furnish the impacts, in which case it would be desirable to provide the end 52 of the hammer unit with a replaceable head, or provide a rod which is specially hardened, to resist random wear or deformation.

While a certain preferred embodiment has been shown and described, modifications will be apparent, in the light of this disclosure, and the invention should not, therefore, be deemed as limited, except insofar as shall appear from the spirit and scope of the appended claims.

We claim:

1. A crimping tool for edge folding of interlocking corners, in sheet metal work, comprising a generally rec-

tangular block, with parallel faces, and of constant thickness, having a U-form notch in its top edge, and a handle extending perpendicularly from one of said faces, a hook-form guide element of right-angular form in cross section, 5 with one flange secured to said top edge of said block and extending perpendicularly from the inner face of said block, on the side opposite said handle, and having a notch coextensive in width with the notch in the block, and the other flange parallel to said inner face of said block, spaced therefrom, and having a notch communicating with the notch in said one flange, coextensive in width therewith, and terminating medially of the depth of said other flange, a cylindrical sleeve, a pair of supporting struts secured to said sleeve at diametrically opposite locations 10 thereon, near the upper end thereof, arranged in a plane at an oblique angle to the axis of said sleeve, and having inturned lower ends of circular cross section, journaled in opposite side edges of said block, a reciprocating rod pivotally mounted for sliding movement in said sleeve and 15 longitudinally-extending in alignment with the notch in said block, said rod having inner and outer end portions extending beyond the respective ends of said sleeve, a head on the inner portion of said rod and located below the adjacent end of said sleeve, a coil spring surrounding the 20 outer end portion of said rod, detent means on the outer end portion of said sleeve engageable by said spring to urge said head against said sleeve, and a reduced upper end on the outer end portion of said rod, for receiving the output end of a reciprocating power tool.

30 2. A crimping tool for folding the edges of sheet metal, comprising a generally rectangular block, with parallel faces, having a notch in its top edge, and a handle extending from one of said faces, a hook-form guide element comprising a pair of tabs secured to said top edge of said block, on opposite sides of said notch, perpendicular to said faces, and extending from said block on the side opposite said handle, a skirt depending from said tabs, in spaced relation to the other of said faces of said block, 35 parallel thereto, a sleeve, a pair of supporting struts secured to said sleeve at opposite locations thereon, near the upper end thereof, arranged in a plane at an oblique angle to said sleeve, and having inturned, lower ends journaled in opposite side edges of said block, and positioning said sleeve for registration with said notch in said block during 40 swinging movement, a reciprocating rod pivotally mounted for sliding movement in said sleeve and longitudinally-extending in alignment with the notch in said block, said rod having inner and outer end portions extending beyond the respective ends of said sleeve, a head on the inner end portion of said rod and located below the adjacent end of said sleeve, a coil spring surrounding the outer end portion of said rod, and detent means on the outer end portion of said rod engageable by said spring to urge said head against said sleeve.

45 3. A tool for folding edges of sheet metal comprising a block having a plane face and a notch in one edge, a hook member carried by said one edge, on opposite sides of said notch and having a skirt portion parallel to, and spaced from, said plane face, with a free edge terminating 50 substantially opposite the innermost portion of said notch, and a sleeve carried by said block and having a reciprocable, inner rod, said sleeve mounted for swinging movement in a plane transverse to said plane face and passing through said notch, and the innermost end of said sleeve spaced from said innermost portion of said notch, said rod being pivotally mounted for sliding movement in said sleeve and longitudinally-extending in alignment with the notch in said block, and having inner and outer end portions extending beyond the respective ends of said sleeve, 55 said sleeve being arranged with its axis at an angle to its radius of swing.

60 4. A tool for folding edges of sheet metal comprising a block having a plane face and a notch in one edge, a hook member carried by said one edge, on opposite sides of said notch and having a skirt portion parallel to, and

spaced from, said plane face, with a free edge terminating substantially opposite the innermost portion of said notch, and a sleeve carried by said block and having a reciprocable, inner rod, said sleeve mounted with its axis in a plane transverse to said plane face and passing through said notch, and the innermost end of said sleeve spaced from said innermost portion of said notch, said rod being pivotally mounted for sliding movement in said sleeve and longitudinally-extending in alignment with the notch in said block, and having inner and outer end portions extending beyond the respective ends of said sleeve.
